US0D1104084S

(12) **United States Design Patent** (10) Patent No.: **US D1,104,084 S**
(45) Date of Patent: ** Dec. 2, 2025

(54) **COLD PLANER**

(71) Applicant: **Caterpillar Paving Products Inc.**,
Brooklyn Park, MN (US)

(72) Inventors: **Michael Scott Hemry**, Maple Grove,
MN (US); **Jason A. Haro**, Dayton, MN
(US)

(73) Assignee: **Caterpillar Paving Products Inc.**,
Brooklyn Park, MN (US)

(**) Term: **15 Years**

(21) Appl. No.: **29/901,131**

(22) Filed: **Aug. 29, 2023**

(51) LOC (15) Cl. **15-03**

(52) U.S. Cl.

USPC **D15/128**

(57) **CLAIM**

The ornamental design for a cold planer as shown and described.

DESCRIPTION

FIG. 1 is a perspective view of a cold planer showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the cold planer which form no part of the claimed design.
